DEVICE FOR TENSIONING OUTSIDE WIDTHS
OF SLIT STRIP

Vernon J. Kegg, Leechburg, Pa., assignor to United States Steel Corporation, a corporation of New Jersey
Filed Feb. 9, 1961, Ser. No. 88,172
3 Claims. (Cl. 242—75.3)

This invention relates to a device for tensioning metal strip as it is coiled following a slitting operation.

After a wide metal strip is slit lengthwise to form a plurality of narrow strands, conventional practice is to pass the strands around a tensioning roller, which carries separator plates, and thence wind them on a single coiling mandrel. Metal strip intended for slitting commonly is rolled on a slightly crowned roll. Pressure on the necks of a crowned roll and consequent deflection of the shaft causes the side edges of a strip to be rolled slightly thinner and more elongated than the remainder of the strip. When the strands are coiled after slitting, the outermost strand on each side, being longer than the others, sags, tends to weave laterally, and may interfere with winding adjacent strands.

An object of the present invention is to provide a tensioning device which overcomes sagging in the outermost strands as they are coiled following a slitting operation.

A further object is to provide a device for applying extra tension to the outermost strands beyond that applied to the other strands through the regular tensioning means.

A more specific object is to provide, in combination with a tensioning roller and a coiling mandrel, an extra tensioning device which includes a spring-held arm pivoted to the support for the tensioning roller and an additional tensioning roller journaled to the arm and riding against the outermost strand.

In accomplishing these and other objects of the invention, I have provided improved details of structure, a preferred form of which is shown in the accompanying drawing, in which:

FIGURE 1 is an end elevational view of a coiling mandrel and tensioning mechanism equipped with an additional tensioning device of my invention; and

FIGURE 2 is a front elevational view of the structure shown in FIGURE 1.

The drawing shows a mandrel 10 for coiling a plurality of narrow metal strands S and S₁ immediately after they have been cut to width by slitting a single wider strip. The mandrel is journaled in a housing 12 and is power driven by suitable mechanism, not shown. A shaft 13 is pivoted to the housing above the mandrel on the side opposite that from which the strands enter. Shaft 13 carries a tensioning mechanism formed of spaced arms 14 and 14a and a tensioning roller 16 journaled to the free ends of the arms. Roller 16 carries a plurality of separator plates 17. Strands S and S₁ coming from the slitting mechanism (not shown) pass around roller 16 and thence wind on the mandrel. Plates 17 keep the individual strands separated, while the roller aids in tensioning the strands. Shaft 13 has a segment which extends outwardly of the mandrel housing 12 and carries a crank arm 18. A fluid pressure cylinder 19 is pivoted to the housing on trunnions 20, and contains a reciprocable piston and piston rod 21, which is connected to the crank arm for operating the tensioning mechanism. The structure thus far described is conventional and not of my invention; hence no more detailed showing is deemed necessary.

As already mentioned, the outermost strands S₁ are more elongated than the other strands S and hence tend to sag. In accordance with my invention, a shaft 22 extends across the space between the two arms 14 and 14a parallel with the axis of roller 16. A pair of downwardly

2

curved arms 23 and 23a are pivoted to shaft 22. Arms 23 and 23a are adjustable lengthwise of the shaft but normally are situated near its ends. Retainers 24 hold arms 23 and 23a in adjusted position on shaft 22. Additional tensioning rollers 25 and 25a are journaled to the lower ends of arms 23 and 23a respectively on axes parallel to shaft 22 and extend inwardly from the arms. An angle iron 26 also is fixed to the two arms 14 and 14a and extends across the space between these arms above shaft 22. The angle iron has a leg which lies perpendicular to the upper edges of the arms and has a plurality of slots 27. Flexible resilient members formed of chains 28 and 28a, tension springs 29 and 29a, and clevises 30 and 30a are connected between angle iron 26 and the respective curved arms 23 and 23a. I can insert different links of chains 28 and 28a in different slots 27 to connect the chains to the angle irons, whereby I can vary the upward force on the curved arms and also can position the chains to correspond with the location of these arms along shaft 22.

In operation I position the curved arms 23 and 23a along shaft 22 so that the additional tensioning rollers 25 and 25a underlie the two outermost strands S₁ ahead of roll 16. Spring tension on these arms supports the outermost strands and applies extra tension thereto and thus prevents their sagging. The tensioning roller 16 moves upwardly as the coils are wound, and my curved arms and additional tensioning rollers of course move with it.

From the foregoing description, it is seen that my invention affords a simple device for applying additional tension to the outermost strands to prevent sagging. The device is readily adjustable for different strip widths and different degrees of sagging. The device can be added to existing installations without otherwise altering their structure.

While I have shown and described only a single embodiment of my invention, it is apparent that modifications may arise. Therefore, I do not wish to be limited to the disclosure set forth but only by the scope of the appended claims.

I claim:

1. The combination, with a mandrel for coiling a plurality of metal strands formed by slitting a strip which is wider than the individual strands, a housing in which said mandrel is journaled, and a tensioning mechanism which includes a pair of spaced apart arms pivoted to said housing, a tensioning roller journaled to said arms, and a plurality of separator plates carried by said roller, said roller being adapted to have the strands pass therearound between said plates before the strands reach said mandrel, of a device for preventing the outermost strand on each side from sagging comprising a pair of arms pivotally related to said first named arms, additional tensioning rollers journaled to the respective second named arms and adapted to engage the outermost strands ahead of said first named roller, and tensioning means connected between said first and second named arms.

2. The combination, with a mandrel for coiling a plurality of metal strands formed by slitting a strip which is wider than the individual strands, a housing in which said mandrel is journaled, and a tensioning mechanism which includes a pair of spaced apart arms pivoted to said housing, a tensioning roller journaled to said arms, and a plurality of separator plates carried by said roller, said roller being adapted to have the strands pass therearound between said plates before the strands reach said mandrel, of a device for preventing the outermost strand on each side from sagging comprising a shaft extending between said arms, a pair of downwardly curved arms pivoted to said shaft, additional tensioning rollers journaled to the respective second named arms and extending inwardly

therefrom to engage the outermost strands ahead of said first named roller to the exclusion of the other strands, and tensioning means connected between said first and second named arms.

3. The combination, with a mandrel for coiling a plurality of metal strands formed by slitting a strip which is wider than the individual strands, a housing in which said mandrel is journaled, and a tensioning mechanism which includes a pair of spaced apart arms pivoted to said housing, a tensioning roller journaled to said arms, and a plurality of separator plates carried by said roller, said roller being adapted to have the strands pass therearound between said plates before the strands reach said mandrel, of a device for preventing the outermost strand on each side from sagging comprising a shaft extending between 10 15

5 said arms, a pair of downwardly curved arms pivoted to said shaft and being adjustable lengthwise of the shaft, additional tensioning rollers journaled to the respective second named arms and extending inwardly therefrom to engage the outermost strands ahead of said first named roller to the exclusion of the other strands, a member extending between said first named arms above said shaft, and tensioning means connected to said second named arms and adjustably connected to said member.
